UNITED STATES PATENT OFFICE.

VERNON D. BEATTY, OF DETROIT, MICHIGAN.

CARD GAME.

Application filed February 19, 1925. Serial No. 10,225.

To all whom it may concern:

Be it known that I, VERNON D. BEATTY, a citizen of the United States, residing at Detroit, county of Wayne, State of Michigan, have invented a certain new and useful Improvement in Card Games, and declare the following to be a full, clear, and exact description of the same, such as will enable others skilled in the art to which it pertains to make and use the same, reference being had to the accompanying drawings, which form a part of this specification.

This invention relates to a card game, and has for its object a series of selectively marked cards adapted to be dealt and played according to certain selected or suggested rules, whose markings make use of the present interest in cross-word puzzle problems, and can be either selected more or less at random or with a view to definite educational features, illustrations of which latter will be hereinafter offered. The game as devised and played will be herein explained with reference to a pack containing sixty cards, in which some of the ideas embodied in the game of "authors" and some employed in the game of "rummy" with regular playing cards are made use of; but I do not desire my disclosure to be understood as restricted thereto in either sense, since it will become obvious, as the explanations herein proceed, that other numbers of cards may be used, and other playing rules followed, while still retaining the cross-word puzzle feature of their markings.

In the drawings:

Figure 1 is a representation of the component cards of three of the numbered series complete.

Figure 2 is a diagrammatic representation of the entire set of sixty cards herein selected for explanation, also containing a suggestion of a possible modification which will be explained later on.

Figure 3 is a representation of a matched pair of cards from the same number series, which, when held or secured by any of the players, may be laid on the table as a step toward the completion of his play.

Figure 4 is a representation of a "sequence" or run of three consecutive numbers, which, when assembled in any one player's hand, may be similarly laid upon the table by their holder.

Figures 5 and 6 are suggestive representations of the remnants of two of the players'

hand, and for whose tenure they are penalized if some one of the other players has sooner succeeded in getting rid of all of his cards in accordance with the rules. 60

As already stated, the pack of cards herein selected for illustration contains sixty units, each one of which bears in large figures some one of the numbers 1 to 10 inclusive, so that, except as will be hereinafter explained, each number series consists of six cards. On the face of each card, in addition to its series number, appears either a single word, or a phrase suggestion of a single word appearing on some one of the other 65 cards of that number series. Thus each number series contains three pairs of correlated cards, and in each series of six cards there are four, which, though bearing the same series number, carry wording not pertinent 70 to, or synonymous with, the markings on either of the two remaining cards. Or, as a further complication and incentive to vigilance on the part of the players, the markings on the cards of a series may be so arranged 75 that either of two of the five other cards of a series may be responsive or complementary to the wording on the sixth card of the series.

Depending on the number of persons taking part in the game, a predetermined number of cards are dealt around to the players and the remainder of the pack left stacked, face downward, in the middle of the table, to be drawn from by the players in order. 80 Thus, assuming that six persons were taking part in the game, seven cards might be dealt to each player and the remaining eighteen left in the drawing stack; let it further be assumed that the first person to play found 85 his hand to consist of one card from each of series 1, 2, 5, 7 and 8 and two cards of series 10. He first draws one card from the central stack and compares it with those already in his hand to determine whether it can be made 90 useful in connection with any of those he already has; if it should happen to be the card "jungle" of series 5, and if the card of that series already in his hand was "tangled vegetation," he has matching word and 95 phrase cards which entitle him to lay down the pair, face upward, on the table, thus making that much progress toward getting rid of all of his seven cards, which is the object of the game. If, however, the card he has drawn, is of another series, as for example, series 6, or if the card drawn, though 100

of series 5, carries the phrase "a four wheeled vehicle," which obviously would not be pertinent to "jungle" of the same series already held by him, two courses are open to him: he may either place the just-drawn card face upward in a "discard" pile, or he may combine it with the cards of series 5 and 7 already in his hand to make a "sequence," which he is similarly privileged to lay down face upward on the table, thus diminishing the number of cards he must get rid of, and in addition thereto place on the "discard" pile whatever card in his hand he, for one reason or another, has the least hope of matching up from the drawing stack, or from the top card of the "discard" stack, as and when this latter is built up in the course of the play; obviously the latter course is the more advantageous.

Suppose, furthermore, that the player, with the same initial assortment of cards in his hand, finds that the card drawn will not fit in with any in his hand, but that the two cards of series 10 first dealt him are complementary, that is, one carrying a single word which is apt and responsive to the phrase on the other card of series 10 in his hand. After drawing from the "unknown" stack, or if a "discard" stack has been meantime built up, from that, the player may put down the pair face upward, as that much of a step toward getting rid of all of his cards, and in addition may discard the card just drawn or any other one in his hand that he sees fit to. The play then goes to the next person at the table, who proceeds similarly, according to what he draws and what he may already have in either matchable or sequence material in his hand. If, however, any one of the players has laid down a sequence, the other players should be vigilant to note and get rid of, either by discarding either from their own hands or from their drawings from either stack, "unknown" or "discard", the three cards, one from each of the number series present in the sequence, whose inscriptions are complementary to the wording on the cards in the sequence or run of three; for example, suppose the sequence laid down consisted of the cards "pearl" of series 3, "belt" of series 4, and "jungle" of series 5, the cards thereafter to be considered especially worthless, except possibly for building up some other "sequence" would be "found in an oyster" of series 3, "goes around the middle" of series 4, and "tangled vegetation" of series 5.

The first player to get rid of all of his cards being the winner of any hand, and the other players being penalized in his favor for the total of the series numbers on the several cards still remaining in the hand of each, it is obvious that, as the play with its drawing, matching, and discarding proceeds, generally speaking it is advisable

to continue to hold cards of as low a series number as possible, in order that the penalizing total may be kept as small as possible, if the player does not succeed in winning the hand by getting rid of his cards first. A variety may, however, be added to the rules of the game, if desired, along the lines suggested in the row representing series 10 in Figure 2, wherein, in place of there being six units of series 10, there are but four, and the other two cards required to make up the total of 60 in the pack may consist of a pair, one containing a phrase and the other containing a single word responsive thereto, but bearing a much higher series number as, for example, 25. Of course as the cards are dealt, no one knows just what the holdings of the others are, or what may still be in the drawing stack, so any one of the players drawing one of these high numbered cards must bear in mind that, instead of there being five other cards of that number series distributed somewhere among the participants in the game, or else held in the drawing stack, there is but one chance of his card being matched so that he can throw down the pair, either by drawing from the "unknown" stack or from a discard by one of his opponents. The ridding of his hand of this large scoring number before any of the other players can complete his matching-up of cards and exhaustion of his hand is consequently the wise move under most circumstances. It is of course obvious that more than one series of six could be thus diminished in favor of a pair of higher numbered cards and that, if desired, some special scoring reward could accrue to the person daring to hold one of these cards long enough to secure the other by drawing and thus constituting a pair.

In Figures 5 and 6, which, as stated, represent the make-up of what might be left in the hands of the least successful players in any one hand, it is obvious that the player still holding the cards represented in Figure 5, when some one of the other players has gotten rid of the last of his cards, would be penalized a total of forty-one points, while the holder of the hand shown in Figure 6 would be penalized twenty-four points.

It is obvious that a wide variety of subjects, either entertaining or educational, could be selected for the phrases and their complementary single words for the markings on any set of cards; in the realm of geography, such pairings, as "the State directly north of Arizona" and "Utah," and in the realm of history "early Norse explorers" and "Vikings," suggest the lines of possibilities in those directions. Furthermore, either an individual deck of cards may be used or several decks with variant basic subjects may be used one after another, in the same way as duplicate whist sets, so that a

familiarity with the titles on any one set, acquired after one or more hands have been played, would not result in a lessening of the players' interest, and would in addition cause a shifting of the lines of thought of the players from one line of words and their synonymous phrases to another.

What I claim is:

1. A card game, consisting of a selected number of cards bearing diverse series markings, each series consisting of a plurality of pairs of cards, one of which contains a phrase and the other of which contains a single word synonymous with such phrase.
10. 2. A card game, consisting of a predetermined number of dealable and drawable cards, each one of said cards bearing a single word synonymous with or suggestive of a phrase appearing on another card, or vice versa, the cards being also marked with diverse series markings whereby the paired cards are located in the same symbolized series with other cards the subject matter of whose markings are irrelevant to them.
15. 3. A cross-word puzzle game, consisting of a plurality of cards each bearing one of a plurality of diverse series markings and in addition a word or phrase suggestive of a phrase or word appearing on one of the

other cards of that series though irrelevant to the subject matter of other cards of the same series.

4. A cross-word game, consisting of a selected number of cards each of which has printed on its playing face a certain series number and a word or phrase suggestive of a phrase or word appearing on another card of the same series, each series containing a plurality of such pairs of cards and the total of the series numbers held by any one player at the conclusion of a game determining the penalty chargeable against him in the scoring.

5. A cross-word game, comprising a plurality of cards each of which carries a series mark and a word or phrase for which a synonym appears on one of the other cards of that series, the cards being playable according to matchings of the words they bear or according to the sequences of series markings.

In testimony whereof, I sign this specification in the presence of two witnesses.
